Design No. 2,782, dated September 24, 1867.

DESIGN FOR A SOLDIER'S MEMORIAL.

The Schedule referred to in these Letters Patent and making part of the same.

TO ALL WHOM IT MAY CONCERN:

Be it known that I, JOHN S. HARRISON, of Canton, in the county of Stark, and State of Ohio, have originated and designed a Soldier's Memorial or Pictorial Soldier's Discharge; and I hereby declare that the following is a full, clear, and exact description of the same, reference being had to the accompanying drawing, forming a part of this specification.

The nature of my invention or design consists in the peculiar arrangement of a blank form for a soldier's discharge, with various pictorial designs, in such a manner as to form a highly ornamental and harmonious picture, the object being to obtain a soldier's memorial, which the friends of deceased soldiers can have filled out with the name, rank, and description of the deceased, and the number of the company and regiment to which he belonged; thus having in a neat form the whole military history of the deceased preserved in a picture; and a second object being to preserve a copy of the living soldier's discharge in a form suitable for framing as a picture.

My design and invention will be readily understood from the accompanying drawing. In the centre is arranged a blank form for discharge from the United States service, which is to be filled out with the name, company, regiment, and so forth, of the soldier, together with the place of discharge, and the name of the discharging officer. At the top and centre is a picture representing the surrender of Lee, being typical of the end of the war. At the bottom and centre is a camp scene, and on the four corners are pictures of the prominent generals. At the top of the blank form, and at the sides of the picture of the surrender of Lee, are collections of cannons, guns, and flags, the instruments of war.

What I claim as my production, and desire to secure by Letters Patent, is--

The design for a soldier's memorial or pictorial soldier's discharge, substantially as shown and described.
